[57] CLAIM

I claim the ornamental design of a golf green tool, as shown and described.

DESCRIPTION

FIG. 1 is front perspective view of the golf green tool of the present invention with the prongs retracted;

FIG. 2 is side view in elevation of the tool as seen from the right of FIG. 1 with the prongs retracted;

FIG. 3 is side view in elevation of the tool as seen from the left side of FIG. 1 with the prongs retracted;

FIG. 4 is a top plan view of the tool of FIG. 1 with the prongs retracted;

FIG. 5 is a bottom plan view of tool of FIG. 1 with the prongs retracted;

FIG. 6 is a front view in elevation of the tool of FIG. 1 with the prongs retracted;

FIG. 7 is a rear view in elevation of tool of FIG. 1 with the prongs retracted;

FIG. 8 is front perspective view of the golf green tool of the present invention with the prongs extended;

FIG. 9 is side view in elevation of the tool as seen from the right side of FIG. 1 with the prongs extended;

FIG. 10 is side view in elevation of the tool as seen from the left side of FIG. 1 with the prongs extended;

FIG. 11 is a top plan view of tool of FIG. 1 with the prongs extended;

FIG. 12 is a bottom plan view of tool of FIG. 1 with the prongs extended;

FIG. 13 is a front view in elevation of the tool of FIG. 1 with the prongs extended; and,

FIG. 14 is a rear view in elevation of tool of FIG. 1 with the prongs extended.
